Attorney

UNITED STATES PATENT OFFICE

WALTER P. MURPHY, OF CHICAGO, ILLINOIS, ASSIGNOR TO UNION METAL PRODUCTS COMPANY, OF CHICAGO, ILLINOIS, A CORPORATION OF DELAWARE

DEVICE FOR OPERATING CAR COUPLERS

Application filed February 27, 1929. Serial No. 343,156.

The invention relates to devices for operating railway car couplers and is especially adapted to that type of coupler having a "rotor" mounted thereon which upon being rotated operates the coupler; that is, unlocks the knuckle; throws the knuckle and/or puts the coupler in lock set position. Some railroads prefer a device which operates the coupler by pushing a handle downwardly in a vertical plane and the object of my invention is to provide a device which is operated by such a vertical plane motion and is adapted for use with a rotor type coupler.

A further object of the invention is to provide such a device wherein the parts can be proportioned and dimensioned so as to obtain great power for operating the coupler.

Another object is to provide such a device which will accommodate the various service movements of the coupler without binding or distorting any of the component parts thereof.

In the drawings:

Fig. 1 shows a typical application of the device to a railway car.

Fig. 2 shows a front elevation of the device and a fragmentary part of the car.

Fig. 3 is a perspective view of the rotating rod and pinion.

Fig. 4 is a perspective of the connecting member.

Fig. 5 shows the connection between the rotating member and the rotor which forms a part of the coupler.

The usual parts of the car are shown, such as end wall 1; striking casting 2; coupler 3 and coupler rotor 4.

My device comprises a rotating member 6 which is hooked into the eye 7 of the rotor 4 of the coupler or connected thereto in any convenient manner. The outer end of this rotating member is non-circular, or preferably square, (8) so as to provide a non-rotative engagement with the pinion 9 which is loosely and slidably mounted thereon. A connecting member 10 is mounted upon the car and the operating lever 11 is pivotally mounted thereon by pin 12 to move substantially in a vertical plane. The lever is provided with a handle or pedal 14 positioned

adjacent the side of the car for convenience of operation and the inner end is provided with a rack 15 which engages the pinion so that an upward or downward movement of the handle will rotate the rotating rod 6.

The pinion 9 is slidably mounted on the rotating member to permit the coupler to accommodate the lateral service movements of the coupler without affecting the relation between the pinion and the rack. The connecting member is so designed (at 17) to permit the rotating member to pass by the lever fulcrum without interference. The connecting member is pivotally mounted upon the car (18) to permit the coupler to move backwardly and forwardly in service without binding any of the component parts of the device.

The connecting member 10 is provided with a pocket which in the structure illustrated (Fig. 4) is formed by the inner wall 20; outer wall 21 and end walls 22-23. The inner and outer walls are provided with apertures 24 for engagement and support of the outer end of the rotating member 6. The pinion 9 is mounted on the rotating member in this pocket and the rack 15 on the operating lever is also confined in this pocket when in engagement with the pinion; in other words, the end wall 22 retains the rack in operative relation to the pinion. The outer wall 21 is preferably removable from the connecting member so that the device can be taken apart. The connecting member 10 is preferably provided with upper and lower wings 26 for engagement with the fulcrum member 27 which is mounted on the car.

Fig. 5 shows a fragmentary part of a coupler having a rotor 4 mounted thereon by wings 28, which rotor is connected to the lock lifter 29 for operating the coupler. For fuller description of this type of coupler reference is made to Kinne Patent No. 1,639,300 of August 16, 1927.

The accompanying drawings illustrate the preferred form of the invention, though it is to be understood that the invention is not limited to the exact details of construction shown and described, as it is obvious that various modifications thereof within the scope

of the claim will occur to persons skilled in the art.

I claim:

5 A device for operating a car coupler comprising a rotor supported by the coupler, a bracket fulcrumed upon the car for movement in a horizontal plane, a rotatable rod with its inner end operatively attached to the rotor and its outer end provided with a pinion, said rod having its outer end mounted upon said bracket so as to permit its inner end to accommodate the service movements of the coupler, and an operating lever mounted upon said bracket to move only in
10 a substantially vertical plane and provided with a rack which engages the pinion.
